AUTOMATIC IRONING MACHINE

Charles E. Molhagen, Walled Lake, Mich., assignor to Ironrite, Inc., Mount Clemens, Mich., a corporation of Michigan

Application May 23, 1955, Serial No. 36,171

Term of patent 7 years

(Cl. D49—1)

Figure 1 is a front elevation view of the automatic ironing machine embodying my new design;

Figure 2 is a view showing the appearance of the left-hand end of the machine of Figure 1;

Figure 3 is a view showing the appearance of the right-hand end of the machine of Figure 1;

Figure 4 is a plan view of the machine shown in Figure 1; and

Figure 5 is a front perspective view of said machine.

It is to be understood that the mesh shown only on part of the screen in Figures 1 and 5 covers the entire screen.

I claim:

The ornamental design for an automatic ironing machine, as shown and described.
